UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

BURNER.

1,256,243.

Specification of Letters Patent. Patented Feb. 12, 1918.

Application filed July 28, 1917. Serial No. 183,220.

To all whom it may concern:

Be it known that I, HENRY C. MAUL, a citizen of the United States of America, residing at Detroit, in the county of Wayne 5 and State of Michigan, have invented certain new and useful Improvements in Burners, of which the following is a specification, reference being had therein to the accompanying drawings.

- 10 This invention relates to burners and has special reference to that kind of burners used in ranges, hot plates, ovens and various types of stoves and heating apparatus utilizing natural or artificial gas for fuel.
- 15 My invention aims to provide a burner, which compared to the well known type of "star" or "spider" burner, possesses the following characteristics and advantages:— First, the burner is materially decreased in 20 size without sacrificing efficiency and with a consequent saving in material; second, without any modifications or changes the burner may use artificial or natural gas as a fuel; third, the arrangement of gas jets insures a large flame area even though the 25 burner is small, and, fourth, the reduction in size and standardizing for natural and artificial gas is a great saving and an advantage for manufacturers, since it is unnecessary to carry in stock different kinds 30 or sizes of burners.

The above and other advantages are gained by a burner structure that will be hereinafter described and then claimed, and reference will now be had to the drawing, wherein—

Figure 1 is a plan of the burner;

Fig. 2 is a cross sectional view taken on the line II—II of Fig. 1; and

40 Fig. 3 is a similar view taken on the line III—III of Fig. 1.

In the drawing, the reference numeral 1 denotes a burner or gas supply pipe and at the outer end thereof is a bowl shaped burner 45 chamber 2 having the side walls thereof crenelated or provided with radially disposed communicating jet chambers 3, and these chambers have convex upper walls 4 merging into the convex upper wall 5 of the 50 burner chamber 2. The burner is therefore somewhat "mushroom" shape, and the top wall of each jet chamber has a series of openings 6 of different sizes. The openings 55 are equally spaced and have for their axes lines radiating from the center of the burner

chamber 2 or a point in the axis of the pipe 1. In practice, the openings 6 are disposed about seven and a half degrees apart and said openings are made with drills preferably four numbers apart, with the smallest 60 openings adjacent the wall 5 and said openings gradually increasing to the outer ends of the jet chambers.

The convex wall 5 of the chamber 2 is also provided with openings 7 having the axes 65 thereof radiating from the same center as the axes of the openings 6, but all of the openings 7 are of the same size and preferably the size of the small openings 6. The openings 7 are arranged in two rows, one at 70 right angles to the other, as best shown in Fig. 1, in contradistinction to the radial rows of the openings 6, and such an arrangement assures flame propagation when gas is ignited at any one of the openings 6 or 7. 75 This is a distinct advantage over certain types of spider burners as it is necessary to ignite the gas at many points before all jets are burning.

The arrangement of the jet chambers permits of gas being equally distributed throughout the burner and by radially disposing the openings 6 and 7 and varying the same in size, a large flame area is obtained presenting a flat heating surface. This is 80 brought about by gradually increasing the size of the jet openings from the central portion of the burner to the extremities thereof, so that there will be a greater gas outlet 85 around the edges of the burner and thus 90 allow larger flames to be maintained at such angle that the tips of the flames will be in the same plane as those flames burning at the jet openings 7. By disposing the jet openings at an angle another very important 95 advantage is gained which contributes to a thorough combustion and consequently a high heat beneath a cooking utensil placed above the burner to be heated thereby. In the manufacture of gas ranges and stoves, 100 what is known as "flame suffocation" is to be avoided and such "flame suffocation" is very often found in connection with burners having all of the jet openings vertically disposed and in groups, somewhat similar to a 105 spider burner. Such a burner generally has an air opening through the center to supply secondary air to the gas jets and this leaves a cool spot in the center on the bottom of a 110 cooking utensil. Then again, with a cen-

- trally located flame surrounded by others and the flames impinging against the bottom of a cooking utensil, the outer flames form a wall or barrier, excluding air from the central flame, leaving no egress for the heat produced by the center flames, and consequently the central flames are of low caloric value, smudge a cooking utensil, and in some instances are completely extinguished. This 5
10 flame suffocation is completely avoided in my burner by having the center jets on an outward angle which gives the produced heat an outward motion from center, allowing the inner jets the proper amount of air
15 for combustion, and also directing the heat to flow outward. The angularity of the outermost flames emanating from the burner permits of sufficient air reaching the innermost flames, and consequently there is a
20 proper combustion at all of the flames, particularly the central flames, producing a high degree of heat uniformly distributed on the bottom of the cooking utensil, without any smudging.
25 What I claim is:—
1. A burner having a gas inlet pipe and a chamber at the outer end thereof, said chamber having the walls thereof crenelated and provided with openings, some of which are
30 of greater diameter than others, and all of the openings having the axes thereof radiating from a common point in said chamber.
2. A burner comprising a gas inlet pipe having a chamber at the outer end thereof, 35 radially disposed jet chambers communicating therewith, and all of said chambers having a common upper convex wall with openings therein radiating from a common point in said burner chamber.
40 3. A burner having a gas inlet pipe provided with a burner chamber having a con-

vex wall provided with openings of equal size disposed in two rows one at right angles to the other, and jet chambers communicating with the burner chamber and having 45 convex walls provided with openings of various size, said openings having the axes thereof radiating from the same center as the axes of the first mentioned opening.

4. A burner of the type described comprising a chamber, jet chambers communicating therewith, said chambers being closed by a convex wall common to all of said chambers and provided with openings, the openings of the jet chambers gradually increasing in size from the burner chamber to the extremities of the jet chambers, and other openings of the same size disposed to assure flame propagation between the first mentioned openings. 50

5. A burner comprising communicating chambers provided with gas outlet openings, said openings being disposed at such angles and of such size as to provide flames, the tips thereof being in a common plane. 55

6. A burner chamber provided with gas outlet openings, said openings being vertical at center, and on an outward angle at its extremities and increasing in size toward its extremities. 60

7. A burner having a substantially spherical shaped top with gas ports on an outward angle and the ports increasing in size from the central portion of the top to the peripheral edges thereof and a gas inlet pipe 75 for said burner.

In testimony whereof I affix my signature in presence of two witnesses.

HENRY C. MAUL.
